CLAIM

The ornamental design for a laser engraver, as shown and described.

DESCRIPTION

FIG. 1 is a top perspective view of a laser engraver design showing my new design.

FIG. 2 is a front view of a laser engraver.

FIG. 3 is a rear view of a laser engraver.

FIG. 4 is a left side view of a laser engraver.

FIG. 5 is a right side view of a laser engraver.

FIG. 6 is a top view of a laser engraver.

FIG. 7 is a bottom view of a laser engraver.

FIG. 8 is a bottom perspective view of a laser engraver.

FIG. 9 is an enlarged view of a laser engraver taken from the circle part in FIG. 2.

FIG. 10 is an enlarged view of a laser engraver taken from the circle part in FIG. 3; and,

FIG. 11 is an enlarged view of a laser engraver taken from the circle part in FIG. 7.

The dash-dash broken lines in the figures depict portions of the laser engraver that form no part of the claimed design. The dash-dot broken lines represent boundaries of the enlarged portions and form no part of the claimed design.

1 Claim, 11 Drawing Sheets
